UNITED STATES PATENT OFFICE.

THOMAS F. FARRELL, OF PATERSON, NEW JERSEY.

ENGINE-VALVE.

SPECIFICATION forming part of Letters Patent No. 367,283, dated July 26, 1887.

Application filed March 24, 1887. Serial No. 232,285. (No model.)

To all whom it may concern:

Be it known that I, THOMAS F. FARRELL, a citizen of the United States, residing at Paterson, in the county of Passaic and State of New Jersey, have invented new and useful Improvements in Engine-Valves, of which the following is a specification.

This invention has for its object to provide novel means for controlling the cut-off of the working-fluid from the cylinder of an engine and to vary the point of cut-off. This object I accomplish in the manner and by the combination of devices hereinafter described and claimed, reference being made to the accompanying drawings, in which—

Figure 1 represents a longitudinal section of a steam-chest containing my improved valve. Fig. 2 is a similar section, on a smaller scale than the preceding figure, of a modified form. Fig. 3 is a sectional elevation of an air-compressor plant, showing the invention as applied.

Similar letters indicate corresponding parts.

In the drawings, referring to Fig. 1, the letter A designates the cylinder of a steam-engine of the usual construction, a' a' being steam-ports, and b the exhaust-port. Within the steam-chest B, and on a suitable seat, is arranged a main or slide valve, C, provided with two induction-ports, c c', which extend in a nearly vertical direction through the same. A seat is formed on the upper surface of said valve for two secondary or cut-off valves, D D, all as usual in this type of engine. The main valve C can be reciprocated by the connection of its valve-stem with an eccentric on the engine-shaft, or by any other well-known means. The cut-off valves D D are guided in their motion by a guide-rod, E, which is rigidly secured at each end in the heads of the steam-chest B.

It will be observed that as the main valve C reciprocates on its seat the position of the cut-off valves D D will determine the point at which steam is cut off from the cylinder, and therefore by changing their position the point of "cut-off" is correspondingly varied.

To effect a change in the position of said cut-off valves as the speed of the engine varies, due to the fluctuations in the load, I connect the same with the stem f of a regulator or governor, F, which latter, as in Fig. 1, is actuated from a moving part of the engine, as usual.

The connection of valves D D and governor shown in the drawings consists of two links, g g, which are pivoted to the valves and to a cross-head, h, on the stem f of the governor, which extends through a suitable stuffing-box in the steam-chest. As the speed of the engine increases, the valves D D are moved farther apart and steam is cut off at a smaller fraction of the stroke, and vice versa.

In Figs. 2 and 3 I have shown a different form of governor and valve, these being intended especially for air-compressor plants. In this case the valves D D, Fig. 2, are subjected to the action of the stiff springs G G, which tend to move the same toward each other. These springs encompass the guide-rod E, and their pressure on the valves is adjustable by means of set-screws g' g', which bear against or are connected with a sleeve on the guide-rod. The governor F consists of a cylinder, F', containing a piston, H, the rod h' of which is connected with the valves D D, as before described. The piston is actuated by air from the receiver R, which is led to the cylinder F' by a pipe, R', and enters above or in front of the piston.

The springs G G can be set to any desired pressure, and if the air in the receiver exceed this pressure the cut-off valves D D will be moved to cut off the steam, as will presently be more fully explained.

When the air-compressors are used for supplying air for mining purposes, it frequently happens that air is not used for a considerable period of time, and a high pressure in the reservoir results. To prevent this I make use of the piston-governor, as described, so that when the pressure in the reservoir reaches or exceeds a certain point steam will almost entirely be cut off from the steam-cylinder A of the compressor.

In addition to the regulator, I use the following device: In the air-cylinder A', Fig. 3, is formed a channel, i, which opens at each end of the cylinder, and at its central portion is formed a circular recess for the reception of a spring-pressed plunger, I, which closes off communication between the ends of the cylinder when it fills out said recess. The plunger is connected by a rod with a piston, I', in a cylinder, I'', separated steam-tight from the plunger I. A steam-pipe, J, connects this

cylinder I² with the cylinder F' of the governor, and at a distance below its upper end, so that when the piston H is moved to cut off the steam by the excess of pressure in the receiver, and when it falls below the mouth of the pipe J, the air can make its way to the cylinder I² and depress its piston I', whereby the channel i is cleared and the air drawn into the air-cylinder A' simply is forced around the cylinder from end to end, and no work is done by the compressor. When the pressure in the receiver R falls below the limit set, the piston H is moved upward by the springs G G, and the plunger I is moved to close the channel i in the air-receiver by its spring. The exhaust-air from cylinder I' escapes through pipe J and out through an exhaust-port, h², in the cylinder F'. This port h² is closed by the piston H when in its lowest position.

To regulate the draft of the furnace, of which S is the smoke-flue, I provide a damper, M, for said flue, which damper is fixed to a spindle, to one end of which is attached a weighted lever, N, that is connected by a link, n, with the piston-rod o of a piston, O', moving in a cylinder, O. The lower end of the cylinder is connected by a pipe, P, with the cylinder F at a distance below its upper end, so that when the piston H cuts off the steam at the engine air is admitted to the cylinder O and the piston O' is moved to close the damper S. This cylinder O also exhausts through the pipe P and cylinder F'.

What I claim as new, and desire to secure by Letters Patent, is—

1. The combination of the longitudinally-moving main slide-valve C and its ports, the secondary or cut-off valves D D, movable toward and from each other on the main valve in the same longitudinal direction as the latter, the vertical lengthwise-movable stem, the governor for operating the stem, and the links connected at one end with the stem and at their other ends, respectively, with the secondary valves, so that the lengthwise movements of the stem slide the secondary valves to and from each other on the main valve to vary the point of cut-off, substantially as described.
2. The combination, with the main slide-valve C and its ports, of the secondary or cut-off valves D, the guide-bar E, on which said secondary valves move, the governor, the lengthwise-movable stem, and the links g, connected, respectively, to the valves and to the lengthwise-movable stem, substantially as described.

3. The combination, with a main valve, of the spring-pressed secondary or cut-off valves, a cylinder, a piston thereon subjected to a pressure, and connections between the cut-off valves and the piston, substantially as shown and described.

4. In an air-compressor plant, the combination, with the compressor and the receiver, of the cut-off valves D D for the steam-cylinder, the cylinder F', connected with the air-receiver at one end, and the piston H therein, connected with the cut-off valves, substantially as described.

5. In an air-compressor plant, the combination, with the compressor and the receiver, of the cylinder F', connected with the receiver, the piston therein, the channel i, formed in the air-cylinder of the compressor, the spring-pressed plunger I, the auxiliary cylinder I², connected with the cylinder F', and a piston in the cylinder I², connected with the plunger, substantially as shown and described.

6. The combination of the steam-cylinder A, the slide-valve C, having ports c c, the cut-off valves D D, sliding to and from each other, the governor-cylinder F', the piston H, having the lengthwise-movable stem connected with the cut-off valves, the air-cylinder A', having the channel i, and auxiliary cylinder I², containing the spring-pressed plunger I, having a piston, I', a pipe, J, connecting the auxiliary cylinder with the governor-cylinder, and the air-reservoir connected with the air-cylinder and with the governor-cylinder above the piston in the latter, substantially as described.

7. The combination of the steam-cylinder A, the slide-valve C, having ports c c, the cut-off valves D D, movable toward and from each other, the governor-cylinder F', the piston H therein, having the lengthwise-movable stem connected with the cut-off valves, the damper-cylinder O, containing the piston O', having the piston-rod o, the pipe P, connecting the damper-cylinder with the governor-cylinder, and the damper M, connected with the piston-rod of the damper-cylinder, substantially as described.

In testimony whereof I have hereunto set my hand and seal in the presence of two subscribing witnesses.
